CLAIM

The ornamental design for a buckle for garment belt, as shown and described.

DESCRIPTION

FIG. 1 is a perspective view of a buckle for garment belt showing my new design.

FIG. 2 is another perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof; and,

FIG. 9 is a cross-sectional view taken along line 9-9 of FIG. 5.
